UNITED STATES PATENT OFFICE

2,491,575

KNIFE

John E. Nelson, Webb City, Mo.

Application February 21, 1946, Serial No. 649,236

1 Claim. (Cl. 30—337)

1

My invention relates to knives and more particularly to knives having a removable blade, which is formed by breaking a double-edged safety razor blade lengthwise into two approximately equal parts.

The object of my invention is to provide a knife in which the removable blade is securely and rigidly held.

Other objects of my invention may appear in the following specification describing my invention with reference to the accompanying drawing illustrating a preferred embodiment of my invention. It is however to be understood that my invention is not to be limited or restricted to the exact construction and combination described in the specification and shown in the drawing but that such changes and modifications can be made, which fall within the scope of the claims appended hereto.

In the drawing:

Figure 1 is a vertical sectional view of a knife according to my invention, partly shown in elevation.

Figure 2 is a top plan view of the knife shown in Figure 1.

Figure 3 is an end view of the knife shown in Figure 1, and

Figure 4 is a sectional view taken on line 4—4 in Figure 1.

Referring now to the drawing in detail the knife according to my invention has a handle 10. This handle has a circular cross section and a semi-globular rear end. It is tapering toward the front and has on its front end a cylindrical portion 11, on which a ferrule 12 is mounted and fastened in any convenient manner. The ferrule 12 has a round cross section and the main part of the ferrule is tapered forwardly just like the handle 10. The forward end 13 is shaped cylindrically and has a somewhat smaller diameter than the forward end of the tapering ferrule portion, thereby forming a shoulder 14 on the ferrule. The cylindrical ferrule part 13 has a slot 15 therein, just wide enough to receive a longitudinal half of a double edged safety razor blade therein.

A cap 16 is firmly but removably mounted on the cylindrical part 13 of the ferrule 12 and the bottom 17 of the cap 16 has a slot 18 therein of the same width as the slot 15 in the ferrule portion 13 and coinciding therewith when the cap 16 is mounted on the ferrule.

A guard 19 has a U-shaped cross section and is either permanently fastened onto the cap 16 or integrally formed therewith so that the guard

2

extends forwardly from the bottom 17 of the cap and that the channel formed by the guard will coincide with the slot 18 in the cap bottom.

A plunger 20 is arranged slidably in the cylindrical ferrule portion 13 and has a forwardly extending projection 21 thereon, the inner surface 22 whereof is flattened.

The plunger 20 extends rearwardly into the tapered main part of the ferrule 12 and has a centrally located and axially and rearwardly extending cylindrical lug 23 thereon. A spiral spring 24 abuts the front face of the cylindrical handle part 11 with one of its ends, surrounds the lug 23 and abuts the plunger 20 with its other end, urging the plunger forwardly. A threaded hole 25 extends diametrically through the plunger and is arranged vertically to the flattened surface 22 on the plunger projection 21.

A screw 26 engages this threaded hole 25 and a slot 27 is provided in the ferrule 12 right behind the shoulder 14 to permit the screw 26 to enter therethrough and to slide therein. The screw 26 has a knurled head 28 to facilitate the tightening and loosening of the screw.

When the knife is assembled the slot 27 is located on top and the plunger projection 21 on the bottom.

In the rear end of the handle 10 a razor blade breaker 29 is provided consisting of a headless screw having a diametrical slot 30 therein. A double edged razor blade can easily be broken in two longitudinal parts by inserting its ends into the slot 30.

One such blade portion 31 is inserted in the channel of the guard 19, after the unit consisting of said guard and the cap 16 is removed from the ferrule 12, so that a broken end portion 32 of the blade will extend upwardly inside the cap 16 beyond the slot 18 and the top edge of the guard 19. The screw 26 is loosened in the plunger 20 and the plunger is pulled back in the ferrule by means of the screw head 28. Then the screw is tightened pulling the plunger upwardly in the bore of the ferrule and preventing it from forward movement under pressure of the spring 24. The cap and guard with the blade 31 therein is then mounted on the ferrule and the screw 26 is loosened. The spring forces the plunger 20 forward. The forward face of the plunger engages the end of the plate 31 pressing the upward extending blade portion 32 against the inside surface of the cap bottom 17. At the same time the plunger projection 21 engages the end shoulders 55 formed on all double-edged safety razor blades

with its forward end and with the flattened surface 22. The screw 26 is tightened again securing the plunger 20 against accidental rearward movement and thereby also securing the blade 34 in working position.

Having described my invention what I claim and desire to secure by Letters Patent is:

A knife comprising a handle, a ferrule fixed on one end of said handle and having a recess therein, a cap comprising a cylindrical portion detachably secured on one end of said ferrule, an end-wall secured to one end of said cylindrical portion and having a narrow, diametrical slot therein, and an elongated guard of U-shaped cross-section projecting outwardly from said end-wall with the channel formed thereby coinciding with said slot, said slot terminating short of the edge of said end-wall adjacent the closed side of said guard to provide a shoulder within said cap, a plunger within said ferrule having a projection on the end thereof facing said cap end-wall which projection is disposed opposite the end

of said slot at the open side of said guard, a compression spring between said plunger and the end of the handle within said ferrule, and a screw threaded into said plunger and extending through said ferrule recess for locking said plunger in operative position, said guard being adapted to receive and support a longitudinal half of a conventional, double-edged safety razor blade with one end of said blade-half within said cap engaging said cap shoulder and engaged by the extension on said plunger.

JOHN E. NELSON.
